United States Patent Office

Des. 180,471
Patented June 18, 1957

180,471

PERFUME CONTAINER

Edouard L. Cournand, New York, N. Y., assignor to Lanvin-Parfums, Inc., New York, N. Y., a corporation of New York

Application October 25, 1956, Serial No. 43,512

Term of patent 14 years

(Cl. D86—10)

FIG. 1.

FIG. 2.

FIG. 3.

Fig. 1 is a front elevational view of a perfume container showing my new design;

Fig. 2 is a top plan view thereof; and

Fig. 3 is an enlarged fragmental detail view of the ornamentation shown in Fig. 1, which appears at the upper and lower ends of the complete circumferential wall of the container.

I claim:

The ornamental design for a perfume container, substantially as shown.
